United States Patent Office

Des. 226,518
Patented Mar. 20, 1973

226,518

NUT

Richard H. Wetherill, Morton, and Anton T. Gregg, East Peoria, Ill., assignors to Caterpillar Tractor Co., Peoria, Ill.

Filed Dec. 21, 1970, Ser. No. 26,589

Term of patent 14 years

Int. Cl. D8—08

U.S. Cl. D8—273

FIG. 1 is an isometric view of the nut embodying our new design;

FIGS. 2-4 are front elevational, top plan and bottom plan views, respectively, thereof;

FIGS. 5 and 6 are side elevational and bottom plan views, respectively, of a modified form of the nut illustrated in FIGS. 1-4.

We claim:

The ornamental design for a nut, substantially as shown.
